UNITED STATES PATENT OFFICE.

WILLIAM OTTO ARZINGER, OF NASHVILLE, TENNESSEE.

FLAKE-SPLITTER.

1,333,198.

Specification of Letters Patent.

Patented Mar. 9, 1920.

Application filed November 1, 1917. Serial No. 199,714.

To all whom it may concern:

Be it known that I, WILLIAM O. ARZINGER, a citizen of the United States, and a resident of Nashville, in the county of Davidson and 5 State of Tennessee, have invented a new and useful Improvement in Flake-Splitters, of which the following is a specification.

My invention relates to improvements in flake splitters, more especially those designed 10 for splitting the flakes of graphite, in the refining thereof, and it consists in the combinations, constructions and arrangements herein described and claimed.

An object of my invention is to provide a 15 device by means of which flakes of graphite during the refining process, may be split up so as to be delivered in very fine condition.

A further object of my invention is to provide a flake splitter which not only splits the 20 flakes of graphite but pulverizes any foreign material associated therewith.

A further object of my invention is to provide a device of the type described, which requires relatively little power for its operation, but which will continuously split the 25 graphite delivered to it and will eject it as fast as the splitting operation is concluded.

A further object of my invention is to provide a device of this kind which is very 30 simple in its construction and cheap to manufacture.

Other objects and advantages will appear in the following specification and the novel 35 features of the invention will be particularly pointed out in the appended claims.

My invention is illustrated in the accompanying drawings forming part of this application, in which:

Figure 1 is a sectional view of the device 40 showing the motor which drives it.

Fig. 2 is a face view of a half section of the device.

Fig. 3 is a section through the device showing the exit casing, and

Fig. 4 is a perspective view showing the construction of the splitting disks.

In carrying out my invention, I provide a pair of casing members 1 and 2, respectively, these casing members having outwardly extending flanges 3 which are secured together by a bolt 4 or in any other suitable manner.

The casing members 1 and 2, as will be observed, are preferably of circular shape and

are curved to provide a circular passage 5 having an outlet pipe 6 at the bottom 55 thereof, or in any other suitable position.

The casing member 1 has an integral sleeve 7 which receives the inlet pipe 8, the latter may lead from any suitable source of supply. In a co-pending application it 60 leads from a sand separator which has previously separated portions of sand and foreign matter from the graphite.

On the inside of the casing and parallel with the casing member 1, is a rigid disk 65 which is secured to the pipe 8 or the casing 1, or to both, the idea being to provide a rigid construction. This disk which is shown at 9, has a central opening 10 into which the end of the pipe 8 may project. 70 One face of this disk, to wit: that next to the casing member 1, is flat as shown in Fig. 1, the opposite face of the disk, however, is provided with a series of curved teeth 9^a. These teeth are constructed in the manner 75 clearly shown in Fig. 4. They resemble somewhat, a series of ratchet teeth, the teeth being of greater depth at the outer edge of the disk and narrowing toward the center thereof. The edges of the teeth are curved 80 in the manner clearly shown in Fig. 4.

The casing member 2 is also provided with an integral centrally disposed sleeve 11 arranged to receive the shaft 12 of a motor M, or other suitable source of power. It is convenient to use the motor because, as stated, the device requires relatively little power and a motor may be conveniently used when mounted on a platform 13 which may be secured to the casing member 2 as shown in 90 Fig. 1, or may be an independent support.

Secured to the end of the shaft 12 on the inside of the casing formed by the members 1 and 2, is a disk 14 which is constructed in a similar manner to the disk 9 already described; that is to say, it is provided with teeth 14^a similar to the teeth 9^a and constructed upon substantially the same curves. The disks 9 and 14 having teeth formed on the same curves, when placed opposite each other, are arranged so that the curves cross one another or bend in the opposite directions from one another. The stationary disk 9 is spaced from the revolving disk 14 at approximately one thousandth of an inch. 105 The distance in the drawing is purposely ex-

aggerated, but in practice, the disks are arranged just so that they will clear one another.

On the periphery of the disk 14 is a series 5 of blades 15, these blades being so arranged as to cause a current of air to be discharged from the discharge pipe 6.

From the foregoing description of the various parts of the device, the operation 10 thereof may be readily understood. The motor M is set in operation and the material is delivered through the pipe 8 through the center of the disk 9 and upon the face of the revolving wheel or disk 14. This is running 15 at a high rate of speed and splits the graphite flakes into small particles. One feature of this device is that these particles may have a diameter several times that of the distance between the blades. In other 20 words, the graphite comes out in very fine, thin flakes. The foreign matter which is sand or similar material, is of course, ground very finely by the disks. The product is drawn by the blades, or rather forced by 25 them, outwardly through the tube 6 into any suitable receptacle. The graphite thus treated is of a very fine flaky nature, and is ready to be placed at once upon the market.

I claim:

30 1. In a flake splitter the combination of a casing; a stationary circular disk, in said casing, said disk having a flat surface on one

side and a plurality of similar splitting edges on its other side, said splitting edges being curved and disposed in a plane parallel 35 to said disk, and also having walls substantially perpendicular to the disk as well as smooth lands gradually sloping away from said walls; a second disk disposed in said casing having splitting edges opposed 40 to, spaced from, and crossing those of said first named disk; means for rotating said second disk; and inlet and discharge means carried by said casing, substantially as described.

2. In a flake splitter the combination of a casing; a stationary circular disk in said casing, said disk having a flat surface on one side and a plurality of similar splitting edges being curved and disposed in a plane parallel 50 to said disk, and also having walls substantially perpendicular to the disk as well as smooth lands gradually sloping away from said walls; a second disk disposed in said casing having splitting edges opposed to, spaced from, and crossing those of said first named disk; means for rotating said second disk; a plurality of blades carried by said second disk outside the periphery of said first named disk; and inlet and discharge means carried by said casing, substantially as described.

WILLIAM OTTO ARZINGER.
